UNITED STATES PATENT OFFICE.

ALOIS W. FORSTER, OF CHICAGO, ILLINOIS, ASSIGNOR TO CEMENT-GUN CONSTRUCTION COMPANY, OF CHICAGO, ILLINOIS, A CORPORATION OF ILLINOIS.

PROCESS AND MEANS FOR FORMING CONCRETE.

Application filed October 31, 1925. Serial No. 66,033.

My invention relates to a process of and a means for forming concrete and has for a particular purpose to provide a method and means for forming clean square corners in concrete work wherein a cement gun is employed. Another purpose is the provision of spacing and supporting means for moulding forms for use with a cement gun. Other purposes will appear from time to time 10 in the course of the specification and claims.

I illustrate my invention more or less diagrammatically in the accompanying drawings, wherein—

Figure 1 is a side view of a built up web girder partially covered with concrete;

Figure 2 is a perspective view of one form of clip employed;

Figure 3 is a section on the line 3—3 of Figure 1;

Figure 4 is a section on the line 4—4 of Figure 1;

Figure 5 is a section on the line 5—5 of Figure 1;

Figure 6 is a perspective view of a channel iron illustrating my process of construction;

Figure 7 illustrates the use of my process with reinforced concrete; and

Figures 8 and 9 illustrate my preferred form of clip.

Like parts are illustrated by like symbols throughout the specification and drawings.

Referring to Figure 1 A is the web of a built up box girder stiffened at the bottom by the superposed plates or members A¹ and secured thereto by the angles A² A². A³ is a vertical angle or stiffener applied to the girder A and A⁴ is a similar stiffener formed of two angle members positioned back to back. A⁵ illustrates throughout the figures the coating of concrete applied to the supporting structure.

B generally denominates one form of clip employed, which includes a clip body B¹ from which may be struck out a plurality of tongues or fingers B² B⁸. In the form of Figure 2 a single finger B² is struck out from between two opposed fingers B⁸ all the fingers preferably but not necessarily being laterally displaced from the plane of the clip body B¹. The opposite end of the clip body terminates in a nail member B⁴ associated with which are shoulders B⁵ adapted to limit the penetration of the nail 55 into the substance into which it is driven.

The body is preferably twisted as at B⁶ in order to position the shoulders B⁵ in a plane transverse to the plane of the structural element to which the clip is secured. The nail B⁴ is less liable to crack the board 60 when driven crosswise to the grain of the wood.

Another form of clip, which on the whole I prefer, is illustrated in Figures 8 and 9 which includes any suitable nail or penetrating member G herein shown as an ordinary nail head as at G¹. About the shank of the nail G is gripped a clip consisting of opposed strips of metal G² G³ which may be spot welded or otherwise secured together as at G³ G⁴, axially deformed as at G⁴ G⁴ to conform to the shape of the nail. They terminate at one end in the outwardly bent spacing edges G⁵ G⁵ and at the other in the opposed gripping blades G⁶ G⁶ the ends 70 of which are outwardly flared as at G⁷ G⁷.

Referring to Figure 6, C is an I beam with the upper reinforcing flange C¹ and the lower flange C².

Referring to Figure 7, D D¹ are any suitable reinforcing rods herein shown as imbedded in the concrete D².

E E are strips or forms herein illustrated as relatively broad thin boards into which are driven the clips B.

It will be realized that many changes may be made in the size, shape, number and disposition of parts without departing from the spirit of my invention and that I wish my description and drawings to be taken as 80 in a broad sense illustrative and diagrammatic rather than as limiting me to my specific description and showing.

The use and operation of my invention are as follows:

It is of course common practice to sheath or enclose supporting structures or members, for example structural steel, with a covering of concrete. Under some circumstances it may be preferable to cast or mould the 100 concrete about the metal. In many cases however it is cheaper and better to project the concrete by means of a cement gun against the metal or other substance or object being enclosed. In applying a protective coating of gun projected concrete to supporting structures or surfaces, it is obviously desirable to have clean, square and straight corners and edges. However, the production of a clean well formed and regu- 110

lar corner with projected cement has been a difficult problem and has added unduly to the expense of the operation of cement projection. The result of cement gun projection is often a rounded and irregular surface with irregular corners.

I have solved the problem by employing the following procedure. I may take a thin strip of wood, or other suitable material, of 10 the desired width, 1 x 4, 1 x 5, or 1 x 6, for example, and drive into or secure to it in alignment as many clips or holding members as are necessary to hold the strip or form in place. In practice, one to every 15 three feet is sufficient.

The clips herein shown include opposed fingers or tongues adapted to grip the opposite sides for example of a flange, or structural member, a connecting body, and a nail 20 adapted to penetrate the board or form. These clips may be driven just like nails.

When the clips have been driven into or secured to the board, they may be clipped on or secured to the flange or structural member. In the type herein shown, the grip of 25 the opposed fingers at the opposite sides of the flange is sufficient to hold the board in place.

As examples of the wide range of use I 30 have indicated in Figures 1 to 5 the employment of a structural member with vertical reinforcing angles, and having horizontal bottom flanges. In forming plane faces and clean corners in the concrete projected 35 against such a member, I employ a strip or form with the necessary number of clips, and shoot the concrete against the structural member into the space defined by the form.

The plane side of the form insures a plane 40 flat surface for the concrete thus projected, the surface terminating in a clear corner. It is easy, in manipulating the cement gun, to get a relatively even edge or corner when 45 the concrete is being shot in a space one side of which is closed by such a plane surfaced form.

When the concrete has been shot up to 50 the wooden strip I simply pull off the strip, leaving the nails sticking out of the concrete. The nails are clipped off and as the wooden strip is in practice positioned a half 55 inch or so from the finishing line, the remainder of the concrete may be shot after the strip has been removed, covering up the stub end of the nails that have been pinched off. The finishing layer is indicated at E¹⁰ in Figure 5.

Figure 6 illustrates the process of covering 60 an I beam and Figure 7 illustrates the process applied to reinforced concrete, the clips being secured to reinforcing bars.

The clips illustrated are designed for the ordinary single stiffener and may have an opening for example of about $\frac{3}{8}$ of an inch

65 The same clips may be made of different

widths, depending upon the weight and length of the strip or form employed. Obviously the distance between the opposed fingers and tongues of the clip may be varied to suit the particular member which is to be used and obviously the length of the clip employed may be varied, depending upon the thickness of the desired coating of concrete.

My method may be roughly summarized 75 as consisting of the employment of a spacing and securing clip for spacing a plane sided form at a predetermined distance from a reinforcing or structural member, projecting concrete to imbed the reinforcing member of the structural member and the holding clip, removing the form, and finally breaking off or covering the projecting stub or nail.

I claim:

1. The process of sheathing a structural member with a sharp cornered concrete sheath which consists in positioning a securing member upon a form, applying said member to the structural member to be covered, projecting concrete into the space within such form and imbedding the structural member and the holding member therein, removing said form from the holding member, removing the projecting end of the holding member, and applying an additional coating of concrete over the remaining stub of the holding member.

2. The process of sheathing a structural member with a sharp cornered concrete 100 sheath which consists in positioning a securing member upon a form, applying said member to the outwardly projecting flange of such a structural member and thereby securing the form thereto, projecting concrete into the space within such form and imbedding the structural member and the holding member therein, removing said form from the holding member and applying an additional coating of concrete over the projecting portion of the holding member.

3. The process of sheathing a structural member with a sharp cornered concrete sheath which consists in positioning a securing member upon a form, applying said member to the structural member to be covered, projecting concrete into the space within such form and imbedding the structural member and the holding member therein, removing said form from the holding member, and applying an additional coating of concrete over the projecting portion of the holding member.

4. The method of forming a square corner upon a sheathing of concrete projected 125 against a structural member, which consists in securing a plane surfaced form in spaced relation to the member to be sheathed, projecting concrete into the space within such form and about said member

and imbedding the member, removing the form, and applying an additional layer of concrete after such removal.

5. The method of forming a square corner upon a sheathing of concrete projected against a structural member, which consists in securing a plane surfaced form in spaced relation to the member to be sheathed by means of a holding clip, projecting concrete 10 into the space within such form and about such member and imbedding the member and the clip, removing the form from the clip, and applying an additional layer of concrete after such removal.

15. 6. The process of sheathing a structural member with a sharp cornered concrete sheath, which consists in positioning a securing member upon a form, applying said member to the structural member to be covered, projecting concrete into the space within such form and imbedding the structural member and the holding member therein, and removing said form from the imbedded holding member.

25. 7. The method of forming a square corner upon a sheathing of concrete projected against a structural member, which consists in securing a plane surfaced form in spaced relation to the member to be sheathed by 30 means of a holding clip, projecting concrete into the space within such form and about such member and imbedding the member and the clip, removing the form from the clip.

35. 8. A holding clip for concrete forms comprising a clip body, an opposed pair of grip-

ping members at one side of the clip body, a nail member projecting from the opposite side of the clip body and means on said clip adapted to limit the penetration of said nail member. 40

9. A holding clip for concrete forms comprising a clip body, a pair of opposed gripping members at one side thereof and a nail member projecting from the opposite side 45 thereof.

10. As a new article of manufacture, a holding clip for concrete forms comprising a clip body, a plurality of opposed gripping members integral with said body and 50 offset from the plane thereof and a nail member projecting from said body.

11. As a new article of manufacture, a holding clip for concrete forms comprising a clip body, a plurality of opposed gripping members integral with said body and off-set 55 from the plane thereof and a nail member projecting from said body and outwardly projecting members adapted to limit the 60 penetration of said nail member.

12. As a new article of manufacture, a holding clip for concrete forms, comprising a nail, a plurality of opposed strips of thin stock secured to each other about said nail, the point of the nail projecting beyond one 65 end of said strips, and gripping arms integral with said strips and projecting axially beyond the head of the nail.

Signed at Chicago, county of Cook, and State of Illinois, this 27th day of October, 70 1925.

ALOIS W. FORSTER.
